UNITED STATES PATENT OFFICE.

ABRAHAM B. LIPSCOMB, OF WHEELING, WEST VIRGINIA, ASSIGNOR OF ONE-HALF TO
W. C. LIPSCOMB, OF ST. GEORGE, WEST VIRGINIA.

TOOL HANDLE.

Application filed April 7, 1925. Serial No. 21,292.

To all whom it may concern:

Be it known that I, ABRAHAM B. LIPSCOMB, a citizen of the United States of America, and resident of Wheeling, county of Ohio, and State of West Virginia, have invented certain new and useful Improvements in Tool Handles, of which the following is a specification.

This invention relates broadly to tool handles, and it has for its object to provide a handle for screw drivers, chisels and other forms of hand tools having shanks or stem portions, which handle is adapted for use interchangeably with a variety of different forms of tools and also with various sizes of such tools.

A further object is to provide a handle which is readily applicable to and removable from the shanks or stems of numerous tools, thus to provide for the employment of a variety of such tools in connection with a single handle, with the ultimate end in view to measureably reduce the initial cost, or purchase price, by eliminating the need for a handle on each such tool.

In describing the invention in detail, reference is herein had to the accompanying drawings, in which—

Figure 1 is a side elevation of the invention applied to the shank of a screw driver;

Figure 2 is a longitudinal section of the same; and—

Figure 3 is an inner end elevation of the cap.

Referring to said drawings, 1 indicates generally the main body portion of the handle, preferably made of wood, the same having therein an axle bore 2 for the reception of the metal shank or stem 3^a of a tool 3, which may be any of various hand tools, or may be any of various sizes of said tools. Fitted stationarily upon the outer end of said handle 1 is a metal cap 4 of which the base member 4^a carries centrally of its inner face an integral forwardly projecting cone 5 which is received in a counterbore 6 provided therefor in the outer end of said handle 1. Said cone has therein a central tapered socket 7 of square or other non-circular form adapted for the reception of a correspondingly shaped end portion 3^b formed on the end of the shank 3^a of the tool. The cone has its open end provided with a plurality of short longitudinal slits

8 which divide said end into a plurality of fingers 9 which are more or less resilient and which, in introducing the tapered end 3^b of the tool in the socket, tend to spring outward to a slight extent, thus not only providing for yielding, gripping, or binding engagement between the fingers and the tool, but also between said fingers and the walls of the conical counterbore adjacent to the inner end of the latter. Said fingers preferably have the inner faces of their terminal portions beveled, as shown at 10.

From the foregoing it will be understood that screw drivers of various sizes, as well as other forms of tools, all having shanks or stem portions 3^a of cylindrical or round-rod form of a size to snugly fit the bore 2 of the handle and having tapered ends 3^b adapted to snugly fit the socket 7 of the cone 5, may be used interchangeably with a single handle having the structure hereinafter described.

What is claimed is—

1. A tool handle comprising a body having therein an axle bore for the reception of a tool shank of round-rod form and provided at its outer end with a counterbore, a metal cap mounted upon the outer end of said body and having an integral cone extending into said counterbore, said cone having therein a central tapered socket of non-circular form into which a correspondingly shaped end of the tool shank may be introduced by lengthwise movement and whereby rotation of said shank is prevented.

2. A tool handle comprising a body having therein an axle bore for the reception of a tool shank of round-rod form and provided at its outer end with a counterbore of conical form, a metal cap fixed on the outer end of said body and having an integral cone fitted in said counterbore, said cone having an axial socket of tapered non-circular form for the reception of a correspondingly shaped end of the tool shank and having a plurality of slits in its inner end whereby is formed a plurality of resilient fingers adapted to be sprung outward into binding relation to the body.

3. A tool handle designed for use interchangeably with a plurality of tools having shanks of round-rod form, said handle comprising a body having an axle bore for the reception of such shanks and having a

central counterbore in its outer end, a cap mounted on said outer end of said body, a member carried centrally by the boss portion of said cap and within said counterbore, said member having a tapered non-circular socket therein for the reception of the correspondingly shaped rear end of the

tool shank, said member being slotted to form resilient fingers adapted to be sprung outward by said end into binding relation to the tapered portion of said shank. ¹⁰

In testimony whereof, I affix my signature:

ABRAHAM B. LIPSCOMB.
